[57] CLAIM

The ornamental design for a combined spray bottle and cap, as shown and described.

DESCRIPTION

FIG. 1 is a perspective view of a spray bottle showing our new design, shown without a cap;

FIG. 2 is a front elevation view thereof;

FIG. 3 is a rear elevation view thereof;

FIG. 4 is a side elevation view thereof, the opposite side being a mirror image except for the orientation of the nozzle;

FIG. 5 is a top plan view thereof;

FIG. 6 is a bottom plan view thereof;

FIG. 7 is a perspective view of another embodiment of a combined spray bottle and cap showing our new design; and,

FIG. 8 is a top plan view of FIG. 7.

FIGS. 1—6 are shown without the cap for clarity of illustration.
